UNITED STATES PATENT OFFICE.

ALICIA ENGLAND, OF JASPER COUNTY, MISSOURI.

TOY SEESAW.

1,144,895.

Specification of Letters Patent. Patented June 29, 1915.

Application filed March 1, 1915. Serial No. 11,308.

To all whom it may concern:

Be it known that I, ALICIA ENGLAND, a citizen of the United States, residing at The Conqueror Trust Sub-Division, in the 5 county of Jasper and State of Missouri, have invented certain new and useful Improvements in Toy Seesaws; and I do hereby declare the following to be a full, clear, and exact description of the invention, such 10 as will enable others skilled in the art to which it appertains to make and use the same.

This invention relates to toys, and one of the principal objects of the invention is to 15 provide a spring actuated see-saw toy which will be amusing and entertaining to children, and which will run or operate without requiring a spring motor or other means for moving the balanced teeter board.

20 The foregoing and other objects may be attained by means of the construction illustrated in the accompanying drawing, in which—

Figure 1 is a side elevation of a see-saw 25 toy made in accordance with this invention, and Fig. 2 is a top plan view of the same, certain portions being shown in section.

Referring to the drawing, the numeral 1 designates a rectangular frame having 30 corner braces 2, and extending across the top and bottom of the rectangular frame 1 are bars 3, said bars 3 being disposed substantially in the center of the frame and connected to said bars 3 and extending at 35 right angles thereto are the vertical supports or standards 4, spaced apart, and connected to the inner side of each of said uprights 4 are pivotal members 5. A teeter board 6 is provided at its opposite edges 40 with trunnions 7, said trunnions extending into the ball bearing casings 5, and secured to the opposite edges of the teeter board 6 are suitable fastenings 8. Suitable figures 9 are permanently connected to the board 6 45 near the opposite ends thereof, and said board is exactly balanced on the trunnions 7.

Extending across the top and bottom bars of the frame 1 are boards or supports 9 50 and connected to the upper boards 9 are

spiral springs 10, said springs depending from the boards and provided with a buffer 11 in the contracted free end of the springs. The springs 10^a are connected to the bottom boards 9 and are also provided with bumpers 55 or buffers 11^a, said buffers being formed of rubber or other suitable material, and the springs and buffers being disposed in the path of the end of the teeter board 6.

The operation of this toy may be briefly 60 described as follows: The teeter board is started with the finger and the end of the board coming into contact with the buffers 11 and 11^a will reverse the action of the board and this operation will continue for 65 some time.

From the foregoing it will be obvious that a toy made in accordance with this invention is simple in construction, cannot readily get out of order, and will be very amusing 70 and can be manufactured at slight cost.

Various changes may be made in the details of construction without departing from the spirit and scope of the invention as defined in the claims.

75 What is claimed is:—

1. A toy see-saw comprising a rectangular frame, a teeter board provided with oppositely disposed trunnions, ball bearings for said trunnions, upper and lower springs 80 connected to the frame in line with the outer ends of the see-saw board and buffers in the ends of said springs.

2. A toy see-saw comprising a centrally pivoted teeter board, springs connected to 85 the frame in the path of the outer ends of the teeter board, and figures mounted upon the teeter board.

3. A toy see-saw comprising a balanced teeter board having figures thereon, springs 90 connected to the frame of the toy in the path of the outer ends of the teeter board, and buffers for said springs.

In testimony whereof I affix my signature in presence of two witnesses.

ALICIA ENGLAND.
